UNITED STATES PATENT OFFICE

2,293,981

MANUFACTURE OF RAYON YARN

Arthur L. Jackson, West Asheville, N. C., assignor
to American Enka Corporation, Enka, N. C., a
corporation of Delaware

Application July 24, 1939, Serial No. 286,294

13 Claims. (Cl. 18—8)

This invention relates to rayon and to a process of and apparatus for producing rayon yarn. More particularly the invention is directed to the production of rayon in which the filaments or threads thereof have a non-systematic denier variation in the form of "nubs."

The production of rayon yarns or threads and the utilization of the same in the formation of various types of fabrics has presented many problems due in part to denier variations occurring in the finished yarns or threads as prepared and the normal operations involved in the manufacture of knitted and woven fabrics. Almost from the very inception of the rayon industry, these problems were recognized and there has been a constant and progressive advance in the art, as a result of which rayon fabrics are now offered generally in competition with other standard fabrics. However, during the past few years it has been found that while slight imperfections in the yarns, filaments or threads in the form of denier variations are objectionable, novel effects in a finished fabric may be produced if the filaments or yarns are spun in a manner to produce accentuated denier variations as distinguished from the objectionable imperfections.

In view of this discovery, considerable activity was instigated with a view to providing processes and apparatus for efficiently producing varying denier or "nub" yarns which would form novel and desirable fabrics when woven or knitted.

It was suggested that the manufacture of rayon filaments with intentional systematic denier variations be effected by supplying the spinning solution to the spinnerets in a systematically irregular manner. Additionally, it was suggested that the same result be attained by applying a drag or braking action to the thread during its passage from the spinneret to the drawing off device. Further, it has been proposed to produce such denier variations in rayon threads by causing the spinneret during the spinning operation to alternately approach and retract from the drawing off device. Nevertheless, each of the heretofore proposed methods failed in one or more respects to accomplish the intended result. In the process in which the occurrence of denier variations is effected by the varying of the length of the thread passage between the spinneret and the drawing off device, among other disadvantages, the alternate approach to and retraction of the spinneret from the drawing off device lowers the quality of the thread

due to the resistance encountered in the coagulating bath and, too, only relatively gradual systematic denier variations in the thread can be had by such a process because rapid movement of the spinneret creates a prohibitory motion in the bath. Furthermore, the use of rayon yarns or threads having systematic denier variations is not entirely satisfactory in that undesirable and somewhat monotonous pattern effects exist in fabrics made therefrom.

In the United States Letters Patent of Gustav A. M. Heim, No. 2,220,403, it is proposed to produce rayon filaments, yarns and threads in which the denier variations thereof are non-uniform in length and occurrence. Furthermore, Gustav A. M. Heim in his patent points out that his invention contemplates the formation of rayon filaments which have denier variations of a relatively pronounced character and that such variations are substantially free of systematic recurrence.

This invention contemplates the formation of rayon yarns, filaments or threads, for convenience hereinafter referred to as filaments, which have denier variations that are of a pronounced character and non-uniform so that the thickened or "nub" portions are substantially free of systematic recurrence.

It is an object of this invention to provide a mechanism by which rayon filaments may be efficiently manipulated during the spinning of the same for producing denier variations which are very pronounced and non-systematic in occurrence.

The mechanism contemplated by this invention in its specific preferred embodiment comprises a chain which is movable upon a flat support and provided with cam blocks secured in an irregularly adjusted manner to the chain links for actuating connecting rods which in turn move pivoted arms each of which carries a freely rotatable roller or friction guide for effecting a variation in the path of travel of succeeding portions of the respective filaments being propelled thereover.

Additionally this invention has as an object the provision of a process and apparatus for the production of rayon filaments whereby novel effects will be produced in fabric in which they are incorporated, the novel effects resulting from the non-systematic variations in the denier of the filaments and the character of the "nubs" formed at varying intervals.

The present process and apparatus contemplate forming "nubs" in the yarn by passing

filaments from a spinneret substantially vertically through a bath to a freely rotatable roller and then around a second freely rotatable roller adjacent to and substantially vertically below said first roller. The filaments are drawn off by means of a positively driven godet at a point remote from the spinneret relative to the position of the rollers. The first roller is mounted for a slow movement away from the second roller and a quick return and the "nubs" are formed on succeeding portions of the filaments adjacent to the spinneret.

The effects produced in materials wholly or partly fabricated of filaments having non-systematic denier variations are particularly pleasing because it has been found that such materials when dyed, printed or otherwise colored have varying dyeing characteristics which result in the attainment of multitudinous and unpredictable effects.

Other objects and advantages will be apparent from the following detailed description when considered in connection with the accompanying drawings wherein:

Figure 1 is a view in side elevation of a portion of one form of apparatus constructed in accordance with the present invention and

Figure 2 is a transverse sectional view through the machine shown in Figure 1 illustrating the rollers for the filaments formed by one of the spinnerets together with the mechanism for supporting and moving one of the rollers.

In referring to the drawings in detail, the numeral 10 designates a spinneret positioned as shown in a coagulating bath 11 which extends along the entire length of the spinning machine. A plurality of spinnerets 10 are positioned at spaced intervals within the coagulating bath. From a suitable source (not shown) a spinning solution is caused to be extruded from each of the spinnerets 10 to form filaments 12 in accordance with any of the well known practices. In the case of a wet spinning process as illustrated, the filaments as formed are withdrawn substantially vertically from the coagulating bath 11. This is accomplished by passing the filaments to and around a freely rotatable roller 13, after which they are caused to descend substantially vertically to and around a second freely rotatable roller 14 located in close proximity to said first roller 13. One set of these rollers 13 and 14 is provided for cooperation with each spinneret 10. After the bundle of filaments 12 has passed around the second roller 14, it is led to a respective draw-off godet 15 which is positively driven by any suitable means. The speed at which the filaments are withdrawn is controlled and determined by the R. P. M. of the godet 15 and the collecting device (not shown).

An important aspect of the present invention is the position and location of the set of rollers 13 and 14 with respect to the spinneret 10 and the godet 15. Rollers 13 and 14 are located just above the spinning bath 11 but spaced a material distance from their respective godets 15 for a purpose to be hereinafter more fully discussed. Each roller 13 is carried at the free end of one of a series of pivoted levers 16, the respective levers being pivotally secured to a bracket 17 which is in turn bolted to a portion of the machine frame. Both bracket 17 and lever 16 are provided with a series of apertures 18 so that the fulcrum point of respective levers may be adjusted by the passage of a bolt 19

through corresponding apertures without the necessity for bodily moving the lever.

The movement of the lever 16 about its axis, which is the bolt 19, is brought about by the action of cams 20 attached to a moving chain 21, which cams successively engage a unit 22 which transmits the lifting action of the cams to the lever 16.

The chain 21 is supported and driven by sprockets 23 and 24 which in turn are keyed to shafts 25 and 26 journaled at 27 and 28. Journals 27 and 28 are attached to upstanding L-bars 29 spaced apart by channel bars 30 and 31 which extend the length of the machine and act to

15 maintain the two sprockets in spaced relation. The channel bar 31 acts as a housing for the lower run of chain 21 and the upper channel bar 30 acts as a runway therefor to maintain the same horizontal for the length of its upper run.

20 On the shaft 25 to which is keyed the sprocket 23 there is also keyed a sprocket 32 adapted to be connected to a suitable source of power (not shown) so that the sprockets and the chain carried thereby may be driven. The cams 20 are 25 attached to alternate links of the chains 21, and although the configuration of each cam conforms to every other cam, the spaces therebetween are varied by mounting the cam on the chain at various points along its length, as is clearly shown in Figure 1.

30 At spaced intervals along the upper run of the chain and overlying the cams are a plurality of units 22 which transmit the motion imparted thereto by the cams to each lever 16. While a 35 machine made in accordance with the present invention may involve various numbers of units e. g. 54 to 120 of the type disclosed, since each is identical in operation a single one will be described. The unit 22 comprises a connecting rod 33 having a bifurcated end 34 into the recesses of which a portion of lever 16 is received and held by bolt 35. The connecting rod is guided in its reciprocating path by bearing 36, filter bridge channel 37, spring stop 38 and bearing 39 each attached to the machine frame. A rubber ring 40 is mounted upon the upper surface of bearing 36 and encircles the connecting rod 33. Ring 40 acts to absorb the shock resulting from the engagement of the shoulder of bifurcated end 34 of rod 33 therewith. Mounted on the connecting rod at a point below the spring stop 38 when the rod is in operative position is an adjustable collar 41, and between collar 41 and spring stop 38 a coil spring 42 is interposed, the function of 45 the spring being constantly to urge the connecting rod in a downward direction. At the lower extremity of connecting rod 33 there is another bifurcated member 43 into the recess of which is placed a freely rotatable roller 44 acting as a 50 cam follower. The position of cam follower 44 is 55 directly above the path of travel of the cams 20 in their movement along the upper run of the chain.

60 In order to maintain the cam follower 44 at the proper position above the chain 21 so that the cam follower 44 will lie in the path of the cams when the shoulder of bifurcated member 43 is resting against the rubber ring 40, and consequently, the arm 16 is at the lower limit of its 65 oscillating path, the connecting rod 33 is made in two sections connected together by a turn-buckle 45.

70 In the operation of the spinning machine after the chain has been set in motion by connection to a source of power driving sprockets 32, and

after the usual pumps for causing the extrusion of filaments have been started and the filaments are being drawn off around rollers 13 and 14, the lever 16 will oscillate in a path selected by the positioning of bolt 19.

The variation in tension of the filaments is caused by the movement of levers 16 about their respective axes in response to the reciprocation of connecting rod 33 caused by the successive contacting of cam followers 44 by cams 20 in their movement along the upper run of the chain as indicated by the arrow in Figure 1. Due to the character of the cam surfaces and the speed of the chain, the upward movement of the connecting rods is gradual as the cams pass under respective cam followers. At the upper limit of each cam the cam follower is suddenly released bringing spring 42 into play to cause the lever 16 to abruptly return to its lower position. This operation will be repeated as each cam 20 carried by the chain 21 engages each of the rollers 44, but it will be noted that the intervals between successive engagements will vary according to the relative positions assumed by the selected cam pieces. In view of the fact that an apparatus in accordance with the present invention may involve as many as one hundred and twenty units 22, no repetition of the irregular formation of "nubs" will be had until after a large quantity of rayon filaments has been produced.

While it is not fully known and understood why the present invention is a substantial improvement over past practices, it has been determined that the instant apparatus does provide a variegated and desirable product commercially satisfactory in the market. Probably due to the fact that the roller 13 is located vertically above spinneret 10 and adjacent the spinning bath 11, the formation of appreciably sized short "nubs" is effected near the spinneret 10 in the bath. The vertically rapid drop of the lever 16 carrying roller 13 will release the tension on the filaments momentarily, but long enough to form the "nub" while the slow rise will not materially alter the shape thereof. The long passage of the filaments from the second idler roller 14 to the godet 15 will act to "set" the "nubs" in the filaments and the tension therebetween will be substantially uniform so that the space between the "nubs" on the filaments will be of even denier.

Because of the intermittent non-systematic actuation of lever 16, the recurrence of the "nubs" will be likewise non-systematic. Moreover, due to the varying distances between the cams 20, the vibrations of the unit 22 will vary and effect different sized and shaped "nubs" thereby accentuating the variegated effects.

It is to be understood that various minor changes may be made in the details of the machine disclosed without departing from the spirit of the invention, e. g., in place of the freely rotatable rollers 13 and 14, friction thread guides may be substituted. Additionally, "nubs" of different thicknesses may be produced either through the adjustability of the fulcrum of the lever 16, or through adjustment of the turn-buckle 45.

While the invention applies particularly to filaments of irregularly varying denier produced by the wet or coagulation method and composed of reconstituted cellulose, such as viscose or cuprammonium silk, it may be applied likewise to filaments produced by the dry or evaporative method, more specifically filaments or threads

having as a base cellulose acetate or other cellulose derivatives.

It is intended that the process described, except for that portion thereof relating to the non-systematic production of irregularly varying denier, shall be conducted according to the well known practices in the art.

The methods and apparatus described above are merely representative and it is intended to include all methods and forms of apparatus as will fall within the scope of the following claims.

What is claimed is:

1. An apparatus for producing rayon filaments comprising in combination means for forming filaments, a driven godet, a lever movable in an arcuate path, a freely rotatable roller mounted on said lever, a second freely rotatable roller mounted in a fixed position in the path of the filaments between the godet and the first roller, and means to oscillate said lever so as to vary the distance between said first roller and said second roller while maintaining the distance between the second roller and godet constant.

2. An apparatus for producing rayon filaments comprising in combination means for forming filaments, a driven godet, a freely rotatable roller therebetween, a second freely rotatable roller for said filaments between said godet and said first roller, said first roller being movable within a path with respect to said second roller to vary the distance therebetween, and means to actuate said first roller, said last named means comprising an endless carrier having irregularly spaced cam blocks thereon to effect the movement of said first roller.

3. An apparatus for producing rayon filaments comprising a plurality of means for forming bundles of filaments, a driven godet for each bundle forming means, a freely rotatable roller for respective bundles in their path between said bundle forming means and said driven godet, each of said rollers being movable in a restricted path, and single means for moving each of said rollers at irregularly recurring intervals independently of each other.

4. An apparatus for producing rayon filaments comprising a plurality of means for forming bundles of filaments, a driven godet for each bundle forming means, a freely rotatable roller for respective bundles in their path between said bundle forming means and said driven godet, each of said rollers being movable in a restricted path, and a long endless conveyor having irregularly spaced cams thereon for successively effecting the movement of each of said rollers at irregularly recurring intervals.

5. An apparatus for producing rayon filaments comprising a plurality of means for forming bundles of filaments, a driven godet for each bundle forming means, a freely rotatable roller for respective bundles in their path between said bundle forming means and said driven godet, each of said rollers being movable in a restricted path, means having a cam follower thereon connected to each roller, and a long endless conveyor having irregularly spaced cams thereon for successively contacting each of said cam followers at irregularly recurring intervals, thereby to actuate said rollers.

6. In an apparatus for producing rayon filaments including means for forming bundles of filaments, a driven godet and an oscillating guide for each bundle of filaments in their path of travel intermediate said forming means and the driven godet, an oscillating lever for each said

guide having said guide freely rotatably mounted thereon, means including a cam follower attached to each lever, and a driven conveyor operating adjacent said cam followers, said conveyor having irregularly spaced cams thereon each adapted to contact each of said followers independently of each other to actuate each said lever at irregularly recurring intervals.

7. In an apparatus for producing rayon filaments including means for forming bundles of filaments, a driven godet and an oscillating guide for each bundle of filaments in their path of travel intermediate said forming means and the driven godet, an oscillating lever for each said guide having said guide freely rotatably mounted thereon, means for effecting an adjustment of the path of oscillation of said lever, means including a cam follower attached to each lever, a driven conveyor operating adjacent said cam followers, said conveyor having irregularly spaced cams thereon each adapted to contact each of said followers independently of each other to actuate each said lever at irregularly recurring intervals.

8. In an apparatus for producing rayon filaments including means for forming bundles of filaments, a driven godet and an oscillating guide for each bundle of filaments in their path of travel intermediate said forming means and the driven godet, an oscillating lever for each said guide having said guide freely rotatably mounted thereon, means for effecting an adjustment of the path of oscillation of said lever, means including a cam follower attached to each lever, a driven conveyor operating adjacent said cam follower, said conveyor having irregularly spaced cams thereon each adapted to contact and slowly raise and abruptly release each of said cam followers independently of each other to actuate said lever at irregularly recurring intervals, and a means constantly urging said cam followers into the path of said cams.

9. An apparatus for producing rayon filaments having variable "nubs" therein comprising means for forming a bundle of filaments, a driven godet located at a point remote from said filament forming means, a freely rotatable roller mounted for reciprocation substantially vertically above said filament forming means and adjacent thereto, a second freely rotatable roller mounted in a fixed position in close proximity to said first roller and substantially vertically therebelow, and means to actuate said first roller with respect to said second roller at irregularly recurring intervals.

10. An operating mechanism for a rayon fila-

ment producing machine having a freely rotatable roller thereon mounted on a member movable in a path, comprising means including a cam follower connected to said member, a driven endless chain operating adjacent said cam follower, cams on said chain adapted to engage said follower, and means constantly urging said follower into the path of said cams, said cams being connected to alternate links of said chain irregularly spaced.

11. An operating mechanism for a rayon filament producing machine having a freely rotatable roller thereon mounted on a member movable in a path, comprising means including a cam follower connected to said member, a driven endless chain operating adjacent said cam follower, cams on said chain adapted to engage said follower, means constantly urging said follower in the direction of said chain, and means to support a run of said chain, the upper surface of said cams sloping upwardly away from the direction of movement of said chain, said cams being connected to alternate links of said chain at different points on the said chain.

12. An operating mechanism for a rayon filament producing machine having a freely rotatable roller thereon mounted on a member movable in a path comprising a cam follower on said member, a driven endless chain operating adjacent said cam follower, cams on said chain adapted to engage said follower, means constantly urging said follower into the path of said cams, a support for a run of said chain and means enclosing another run of said chain, said cams being connected to alternate links of said chain at irregularly spaced intervals.

13. A process for the production of rayon threads having variable "nubs" therein comprising extruding filaments vertically through a spinneret into a coagulating bath, directly drawing the formed thread substantially vertically and without friction, from the spinneret while in a plastic state under tension, deflecting said thread from its vertical path at a point remote from said bath, slowly increasing the distance of said point of deflection from said bath at irregularly recurring intervals at a rate of speed insufficient to materially alter the cross-section of said thread, and suddenly decreasing the distance of said point of deflection from said bath at the end of each said intervals, whereby "nubs" are formed in the plastic thread adjacent the spinneret, and setting the "nub" formation in the thread by causing the thread to pass through a long path of travel prior to collection.

ARTHUR L. JACKSON.
